Primary Examiner — Janice Patyk

(74) *Attorney, Agent, or Firm* — LUCAS & MERCANTI, LLP

(57) **CLAIM**

The ornamental design for a jug, as shown and described.

DESCRIPTION

FIG. 1 is a top view of a jug, showing my new design; FIG. 2 is a top perspective view thereof;

FIG. 3 is a front view thereof;

FIG. 4 is a right side view thereof;

FIG. 5 is a back view thereof;

FIG. 6 is a left side view thereof;

FIG. 7 is a bottom plan view thereof;

FIG. 8 is a front perspective view thereof; and,

FIG. 9 is a left side perspective view thereof.

The broken lines in the figures illustrate the portions of the jug and form no part of the claimed design.

1 Claim, 9 Drawing Sheets
